HEMSTITCH AND EMBROIDERY SEAM

Albert H. De Voe, Westfield, N. J., assignor to The Singer Manufacturing Company, Elizabeth, N. J., a Corporation of New Jersey

Application April 23, 1932. Serial No. 607,058

7 Claims. (Cl. 112—266)

This invention relates to improvements in seams for sewed articles and has for an object to enhance the ornamental effect of embroidery, hemstitching, picot-edging and like seams.

5 A further object of the invention is to provide hemstitch and picot-edge seams according to which the stitching thread in an improved manner, ties back and effectively holds the body-material threads which are deflected by a piercer 10 during the formation of the hemstitch seam, and which stitching thread, or threads, at the same time more ornamentally and distinctly defines the character of the seam.

The foregoing and other objects and advantages in view, together with the improved seams whereby the same are attained, will best be understood from the following description of embodiments thereof illustrated in the accompanying drawing, in which:

20 Figs. 1 and 2 represent top and bottom plan views of one form of the improved hemstitch or openwork seams produced in a section of a body-material, the stitching being effected by a single thread. Fig. 3 is a bottom plan view of a product 25 according to which the thread-loop concatenations are of a different character at opposite sides of a row of hemstitch-seam apertures. Fig. 4 represents, in perspective, adjacent single- and double-thread chain-stitch seams, illustrated somewhat diagrammatically. Fig. 5 represents a perspective view of a single-thread, ornamental edge-finishing seam, constituting an improved picot-edging.

35 The novel seams illustrated in the accompanying drawing have been produced by a two-needle hemstitching machine disclosed in my patent application Serial No. 605,407, filed April 15, 1932. In hemstitching, a body-material 1 is provided by 40 a piercer with a row or succession of apertures 2 separated by intervening and substantially parallel cross-bars 3 of the body-material. The size and shape of the body-material apertures 2 vary with the type of piercer which may be employed 45 in the hemstitching machine, and the width of the cross-bars 3 is of course influenced by the extent of feed of the work as well as the thread-tension, as will be readily understood.

According to the present invention, the body-material threads are secured to define the openings 2 by two rows of stitches of such a character as to serve to bind the cross-bars 3 and to more effectively tie back the body-material threads at opposite sides of the openings 2, the 55 stitches being of an elastic character and there-

fore also adapted to stretch with the body-material.

Referring more particularly to Figs. 1 and 2 of the drawing, each of these three-stitch figures includes a cross-bar embracing stitch 4 extending in the general direction of the seam line, from one to a succeeding piercer-aperture 2, a lateral stitch 5 out of the seam line and anchored in the body-material opposite to the last entered piercer-aperture, and a return stitch 6 to said last entered piercer-aperture. These stitches are formed by initially passing a loop of thread 7 through a piercer-aperture 2, detaining and spreading said loop below the body-material, advancing the body-material and passing another 70 thread-loop 8 through the next piercer-aperture and through the thread-loop 7. While the body-material remains stationary, a loop of thread 9 is then passed therethrough at a point adjacent to the piercer-aperture in which the loop 8 is 75 disposed, said loop 8 being spread below the body-material to receive the loop 9. A succeeding three-stitch figure is then formed by passing another loop 7 through the piercer-aperture entered by the thread-loop 8, and by enchaining 80 said newly formed loop 7 with the previously formed loop 9. While the thread-loop 9 enters the loop 8 at a point in vertical alinement with the direction of penetration of the body-material by said loop 9, the tightening of the stitches draws the loop 8 along the limbs of the loop 9 in the general direction of the adjacent piercer-aperture 2. The resulting disposition of the enchainable thread-loops outlines the hemstitch seam 85 in a novel and highly ornamental manner, and at the same time serves to very effectively tie back the body-material threads between successive cross-bars 3.

By combining the single-thread chain-stitch seam, before described, with a two-thread chain-stitch seam as illustrated in Figs. 3 and 4 of the drawing, there is produced a contrasting effect enhancing the ornamental appearance of the embroidery seam and particularly in hemstitching. The two-thread seam likewise constitutes repetitions of three-stitch figures, comprising cross-bar embracing stitches 10 disposed in the general direction of the seam line and substantially parallel with the stitches 4 of the previously described seam, said stitches 10 being connected by lateral stitches 11 out of the seam line and return stitches 12 to the seam line, the stitches 11 extending from the side of the stitches 10 in a direction opposite to the direction of 110

lateral extension of the stitches 5 from the
stitches 4.

The two-thread chain-stitches are formed by initially passing a loop of needle-thread 13 through a piercer-aperture 2 and into a loop 14 of looper-thread below the work, after which a loop 15 of looper-thread is passed through the needle-thread loop 13 below the loop 14. After the work has been advanced to the next piercer-aperture 2, a loop 16 of needle-thread is passed therethrough and through the looper-loop 15, and a succeeding loop 17 of the looper-thread is passed through said loop 16. While the body-material remains stationary, a loop 18 of needle-thread is then passed therethrough at a point adjacent to the last entered piercer-aperture. The needle-loop 18 enters the looper-loop 17 and another looper-thread loop 14 is then passed through the loop 18 below the looper-loop 17. A succeeding three-stitch figure is thereafter started by passing another loop 18 through the last entered piercer-aperture and enchaining therewith the looper-thread as previously described.

25 The picot-edge seam illustrated in Fig. 5 may be formed by severing the cross-bars between the two seam lines of Fig. 1, so that single-thread chain-stitches 4 embrace tufts 20 of body-material threads, the specially formed chain-stitches 30 producing a highly ornamental edge-finishing effect, particularly when using stitching thread of a color contrasting from that of the body-material. A picot-edge seam of this character is elastic and is therefore better adapted for finishing 35 the edges of elastic body-materials.

Having thus set forth the nature of the invention, what I claim herein is:—

1. A body-material provided with a row of hem-stitch-seam apertures with intervening cross-bars 40 which are individually bound by the concatenated loops of a single-thread chain-stitch seam anchored in the body-material adjacent each of said apertures.

2. A body-material provided with a row of hem-stitch-seam apertures with intervening cross-

bars secured in spaced relation by a single-thread chain-stitch seam comprising cross-bar embracing enchain loops of a single thread connected by pairs of loops of said thread enchain at the sides of the hemstitch-seam apertures between said cross-bars and anchored in the body-material.

3. A body-material provided with a row of hem-stitch-seam apertures with intervening cross-bars which are individually bound at opposite sides of said cross-bars by single-thread chain-stitch seams.

4. A body-material provided with a row of hemstitch-seam apertures with intervening cross-bars which are individually bound at one side of said apertures by the concatenated loops of a two-thread chain-stitch seam, and are individually bound at the opposite sides of said apertures by the concatenated loops of a single-thread chain-stitch seam.

5. A body-material provided with adjacent rows of single- and two-thread chain-stitch seams, each of which comprises stitches disposed in the general direction of the seam line connected by a lateral stitch out of and a return stitch into said seam line, said lateral and return stitches being disposed at opposite sides of the respective seams.

6. A body-material provided with an ornamental edge-finishing seam comprising concatenated loops of a single thread anchored in the body-material margin and embracing spaced tufts of the body-material projecting beyond said margin.

7. An overedge seam for a body-material constituted by repetitions of a three-stitch figure of enchain single-thread loops, two successive stitches of said figure being anchored in the body-material and embracing the margin of said body-material, with the other stitch of said figure disposed beyond said margin substantially parallel therewith and embracing a tuft of said body-material projecting beyond its margin.
